MAGNETIC DRILL CHUCK ASSEMBLY

David K. Appleby, New Castle, Del.

Application December 11, 1953, Serial No. 397,557

6 Claims. (Cl. 279—16)

This invention relates to magnetic connecting and self-centering means for objects which are otherwise unconnected with each other, and are otherwise not confined to a centered relation to each other, and which are to be rotated in driving and driven relation to each other.

The primary object of the invention is to provide practical, and efficient means of this character which enable quick, accurate, and easy centering of such as micro drills without resort to presently employed various devices and expedients whose employment consumes time and effort, and involves substantial expense for their provision and maintenance.

Another important object of the invention is to provide means of this character indicated above which are composed of a minimum number of simple parts, and which can be made in rugged, serviceable, and attractive forms at relatively low cost.

Other important objects and advantageous features of the invention will be apparent from the following description and the accompanying drawings, wherein, for purposes of illustration only, specific embodiments of the invention are set forth in detail.

Figure 1 is a substantially central vertical transverse section taken through one embodiment;

Figure 2 is a horizontal section taken on the line 2—2 of Figure 1;

Figure 3 is a substantially central transverse vertical section taken through another form of magnetizable chuck member for use with the embodiment of Figure 1;

Figure 4 is an enlarged side elevation of another embodiment of the invention, a drill centering operation being shown as performed with a lead pencil;

Figure 5 is a top plan view, on a reduced scale, of the magnetizable chuck member of Figure 4; and

Figure 6 is a bottom plan view, on a reduced scale, of the magnet-bearing member of Figure 4.

Referring in detail to the drawings, wherein like numerals designate like parts throughout the several views, and first to Figures 1 and 2 thereof, the embodiment of the invention therein shown is generally designated 7.

The assembly 7 comprises a magnet-bearing member 8, here shown as a solid cylindrical body of aluminum or other suitable non-magnetizable material, having a frusto-conical upper portion 9 having an axial socket 10 in which is plug-fitted a shank 11 which is arranged for engagement in the chuck of a drill press or the like (not shown).

The underside 12 of the member 8 is flat and squared with the axis of the member 8, and is provided with a relatively large diameter circular and concentric recess 13, in which is secured, in suitable manner, a circular permanent magnet 14 having a plain underside 14' which is spaced upwardly at a slight distance above the underside of the member 8.

The assembly 7 further comprises the magnetizable chuck member 15 which is here shown as a circular cup having a plain bottom wall 16 and a peripheral rim or side wall 17 rising from the bottom wall 16. The cup

15 is made of aluminum or other suitable non-magnetizable material, secured in the cup 15 and covering the bottom wall 16 is a relatively thin magnetizable plate 18. The internal diameter of the rim 17 is slightly larger than the outside diameter of the cylindrical part of the magnet-bearing member 8. The cup 15 can also be made entirely of steel, if desired.

Preferably formed integral with the cup bottom wall 16 is an axial depending boss 19 which terminates in a chuck head 20 provided with an axial socket 21, arranged to receive the upper end of a micro drill bit 22, the latter being securable in the socket 21 by a set screw 23 traversing the chuck head 20.

Another form of magnetizable chuck member, designated 15' in Figure 3 of the drawings, is the same in construction as the member 15 of Figures 1 and 2, is usable with the magnet-bearing member 8 thereof, but has a different form of chuck head, which involves a slot 24 in the lower end of the boss 19', the provision of external screw threads 25 on the lower end of the boss 19', a bevel 26 on the lower end of the boss 19', and a nut 27 threaded on the threads 25. The bore of the nut 27 is choked at its lower end to provide a cam bevel 28 for compressive engagement with the bevel 26 to clamp a drill bit in the bore of the boss 19'.

In operation, the magnet-bearing member 8 being engaged in a drill press chuck (not shown) and the magnetizable chuck member 15 being engaged over the lower end of the magnet-bearing body 8, with the magnet 14 holding the member 15 in place against the underside 14' of the body 8, and the assembly being rotated by the drill press, fingers of a hand are engaged with the rim 17 and the member 15 is shifted relative to the member 8 to a slightly eccentric or off-center position, this movement being provided for by the larger inside diameter of the rim 17.

The point 29 of a pencil 30, or some other suitable implement, is then applied against the side of the rotating drill bit 22, as illustrated in Figure 4, and manipulated so

as to center the drill bit 22.

The embodiment of the invention shown in Figures 4 through 6 of the drawings, and generally designated 7a, differs from those shown in Figures 1 to 3, only in the provision of equally circumferentially spaced and diametrically opposed notches 31 in the underside 12a of the magnet-bearing body 8a, and in the provision of similarly arranged lugs 32 on the upper edge 33 of the magnetizable chuck member wall 16a. The lugs 32 are slightly narrower than the notches 31, and the lugs 32 are engaged in the notches 31 in the assembled condition of the device 7a, with the lower side 12a of the body 8a resting upon the upper edge 33 of the wall 16a of the member 15a.

The operation of the device of Figures 4 through 6 is the same as with the device 7 of Figures 1 through 3.

The arrangements described hereinabove permit of quickly and easily manually separating the magnetizable chuck members from the magnet-bearing members, while the devices are being rotated, for replacement of drill bits, and other magnetizable chuck members may be substituted for those so removed, whenever desired, and without stopping the associated drill press, or other manipulations or delays.

It is to be noted that the device can be operated in either vertical or horizontal positions with equal efficiency.

What is claimed is:

1. An alignable holder for a drill and the like comprising a shank member, a drill retaining member, magnetic coupling means providing a constant attractive force incorporated in said shank member and said retaining member for operatively engaging said members, said members having planar contacting surfaces to per-

mit lateral movement of said members relative to each other, and said constant attractive force being of sufficient strength to prevent relative angular movement of said members while said drill is cutting, and being weak enough to permit relative lateral movement of said members when a lateral centering force is applied to a retained drill.

2. An alignable holder as set forth in claim 1 wherein said shank member is comprised of a substantially cylindrical member and said drill retaining member is comprised of a cup-shaped member whose inside diameter is larger than the outside diameter of said cylindrical member.

3. An alignable holder as set forth in claim 2 wherein a circular recess is provided in the underside of said cylindrical member, a circular permanent magnet is disposed in said recess, said cup-shaped member is made of nonmagnetic material and a plate of magnetic material forms the bottom wall of said cup.

4. In a magnet drill chuck assembly comprising a magnet-bearing member and a magnetizable chuck member, said magnet-bearing member comprising a cylindrical body having an upper end and a lower end, a shank on the upper end of said body engageable in the chuck of a drill press, the lower end of said body being provided with a circular recess, a circular magnet secured in said recess, said magnet having an underside, said magnetizable member comprising circular cup having a bottom wall and a peripheral rim rising from said bottom plate, the internal diameter of said rim being greater than the outside diameter of said magnet-bearing member body, a magnetizable plate secured upon said bottom plate, and axial drill chuck means fixed to and depending from said bottom plate, the magnetizable plate being frictionally and slidably engaged with the underside of said body and held so engaged by the attraction of said magnet with said rim freely surrounding said body, said magnetizable chuck member being manually shiftable radially relative to the magnet-bearing body to center a drill bit in said chuck means relative to the magnet-bearing body.

5. In a magnet drill chuck assembly comprising a magnet-bearing member and a magnetizable chuck member, said magnet-bearing member comprising a cylindrical body having an upper end and a lower end, a shank on the upper end of said body engageable in the chuck of a drill press, the lower end of said body being provided with a circular recess, a circular magnet secured in said recess, said magnet having an underside, said magnetizable member comprising a circular cup having a bottom wall and a peripheral rim rising from said bottom plate, the internal diameter of said rim being greater than the outside diameter of said magnet-bearing member body, a magnetizable plate secured upon said bottom plate, and axial drill chuck means fixed to and depending from said bottom plate, the magnetizable plate being frictionally and slidably engaged with the underside of said body and held so engaged by the attraction of said magnet with said rim freely surrounding said body, said magnetizable chuck member being manually shiftable radially relative to the magnet-bearing body to center a drill bit in said chuck means relative to the magnet-bearing body.

the internal diameter of said rim being greater than the outside diameter of said magnet-bearing member body, a magnetizable plate secured upon said bottom plate, and axial drill chuck means fixed to and depending from said bottom plate, the magnetizable plate being frictionally and slidably engaged with the underside of said body and held so engaged by the attraction of said magnet with said rim freely surrounding said body, said magnetizable chuck member being manually shiftable radially relative to the magnet-bearing body to center a drill bit in said chuck means relative to the magnet-bearing body, the magnet having an underside, spaced upwardly from the underside of said body.

6. In a magnet drill chuck assembly comprising a magnet-bearing member and a magnetizable chuck member, said magnet-bearing member comprising a cylindrical body having an upper end and a lower end, a shank on the upper end of said body engageable in the chuck of a drill press, the lower end of said body being provided with a circular recess, a circular magnet secured in said recess, said magnet having an underside, said magnetizable member comprising a circular cup having a bottom wall and a peripheral rim rising from said bottom plate, the internal diameter of said rim being greater than the outside diameter of said magnet-bearing member body, a magnetizable plate secured upon said bottom plate, and axial drill chuck means fixed to and depending from said bottom plate, the magnetizable plate being frictionally and slidably engaged with the underside of said body and held so engaged by the attraction of said magnet with said rim freely surrounding said body, said magnetizable chuck member being manually shiftable radially relative to the magnet-bearing body to center a drill bit in said chuck means relative to the magnet-bearing body, the underside of said body being plain and continuous.
